UNITED STATES PATENT OFFICE.

CHARLES E. NORTON, OF DORCHESTER, MASSACHUSETTS.

SAFETY-VALVE.

No. 860,820.

Specification of Letters Patent.

Patented July 23, 1907.

Application filed April 27, 1905. Serial No. 257,689.

To all whom it may concern:

Be it known that I, CHARLES E. NORTON, a citizen of the United States, residing at Dorchester, in the county of Suffolk and State of Massachusetts, have invented new and useful Improvements in Safety-Valves, of which the following is a specification.

This invention relates to safety valves, and the object is to provide a simple, durable safety valve which shall not stick or bind in operation and in which the wear of the valve seat is automatically compensated for.

The invention consists in the combination and arrangement of parts set forth in the following specification and particularly pointed out in the claims thereof.

15 Referring to the drawings: Figure 1 is a central longitudinal sectional elevation of a safety steam valve constructed in accordance with my invention. Fig. 2 is a detail transverse section taken on line 2—2 of Fig. 1.

Like numerals refer to like parts throughout the several views of the drawings.

In the drawings, 8² is a casing having an inlet orifice 9² and a series of outlet orifices 10², said outlet orifices consisting of slots extending longitudinally of the casing 8² and extending entirely therethrough. A cylindrical valve seat 14² is provided in the interior of the casing 8² and is located between the inlet orifice 9² and the outlet orifices 10². A valve 15² provided in its periphery with spring packing rings 19² is slidable longitudinally of the casing 8² and of the valve seat 14² and rests normally upon stops 26 provided upon the interior of the casing 8². A valve stem 16² projects upwardly from the valve 15² and has fast to its upper end a guide plate 27 provided with wings or radial arms 28 which contact at their outer ends with the interior of 30 the cylindrical casing 8².

Two helical compression springs 29 and 30 are inclosed within the casing 8² and bear at their opposite ends against washers 31 and 32. The washer 31 rests upon the top of the guide plate 27 while a screw 33 bears against the top of the washer 32. The screw 33 has screw-threaded engagement with a cap 17² and said cap in turn has screw-threaded engagement with the interior of the casing 8². The screw 33 is used to increase or diminish the tension upon the springs 29 and 30 and is held against rotation by a check nut 34.

The operation of the valve hereinbefore specifically

described is as follows: Steam enters the interior of the casing 8² through the inlet orifice 9² under pressure and presses against the underside of the valve 15². When this pressure increases beyond the amount desired, 55 the valve 15² is moved upwardly until the lower edge of said valve passes beyond the lower edges of the orifices 10². As soon as the valve 15² arrives in the elevated position referred to the steam escapes through the orifices 10², thus relieving the pressure upon the 55 boiler. The spring packing rings 19² will take up any slight amount of wear which may come upon the cylindrical valve seat 14² and thus always preserve a tight joint between the valve 15² and its casing 8².

Having thus described my invention what I claim 60 and desire by Letters Patent to secure is:

1. In a device of the character described, a casing provided with an inlet orifice and a plurality of outlet orifices, a cylindrical valve seat formed in said casing and located between said inlet and outlet orifices, and stops in the 65 interior of said casing below said outlet orifices; in combination with a cylindrical valve adapted to slide longitudinally of said valve seat, a packing device located in the periphery of said valve and adapted to make sliding contact with said valve seat, a valve stem projecting upwardly 70 from said valve, a guide plate fast to the upper end of said stem, said guide plate provided with wings which contact at their outer ends with the interior of said casing, and a spring acting to force said guide plate and valve downwardly, to hold the underside of said valve 75 against said stops.

2. In a device of the character described, a casing provided with an inlet orifice and a plurality of outlet orifices, a cap fast to one end of said casing, a screw having screw-threaded engagement with said cap and projecting 80 therethrough, a cylindrical valve seat formed in said casing and located between said inlet and outlet orifices, and stops in the interior of said casing; in combination with a cylindrical valve adapted to slide longitudinally of said seat, a packing device located in the periphery of 85 said valve and adapted to make sliding contact with said cylindrical valve seat, a valve stem projecting upwardly from said valve, a guide plate fast to the upper end of said stem, said guide plate provided with wings which contact at their outer ends with the interior of said casing, a 90 washer bearing against said plate, another washer bearing against said screw, and a spring bearing at its opposite ends, respectively, against said washers.

In testimony whereof I have hereunto set my hand in presence of two subscribing witnesses,

CHARLES E. NORTON.

Witnesses:

CHARLES S. GOODING,
ANNIE J. DAILEY.
